[57] **CLAIM**

The ornamental design for a scarf and clasp, combination as shown and described.

DESCRIPTION

FIG. 1 is a front perspective view of a scarf and clasp combination showing our new design;

FIG. 2 is a rear perspective view thereof;

FIG. 3 is a perspective view of the scarf portion, shown separately for clarity of illustration, the undisclosed portions thereof following the configuration of the portions shown;

FIG. 4 is a front elevational view of the clasp portion, shown separately for clarity of illustration;

FIG. 5 is a rear elevational view thereof; and,

FIG. 6 is a bottom plan view thereof, the opposite side being a mirror image of the side shown.

The broken line showing of the human form in FIG. 1 is for illustrative purposes only and forms no part of the claimed design.

FIG. 1

FIG. 4

FIG. 5

FIG. 6
